LACE

Filed Feb. 7, 1933

Inventor:
Fannie Gentner

UNITED STATES PATENT OFFICE

91,937

DESIGN FOR LACE

Frederick Gentner, Philadelphia, Pa., assignor to North American Lace Company Incorporated,
Philadelphia, Pa.

Application February 7, 1933, Serial No. 47,141

Term of patent 3½ years

To all whom it may concern:

Be it known that I, FREDERICK GENTNER, citizen of the United States, residing at Philadelphia, in the county of Philadelphia and State of Pennsylvania, have invented certain new, original and ornamental Design for Lace, of which the following is a specification, reference being had to the accompanying drawing, in which the figure is a face view of a piece of lace showing my design.

I claim:

The ornamental design for lace substantially as shown.

FREDERICK GENTNER.
